MACHINE FOR DE-BURRING AND POLISHING
METAL ARTICLES OR THE LIKE

Robert K. Landon, 6094 Morningside Road,
Joshua Tree, Calif.

Filed Dec. 11, 1959, Ser. No. 58,638

Term of patent 14 years

(Cl. D55—1)

Figure 1 is a perspective view illustrating a machine for de-burring and polishing metal articles or the like, showing my new design;

Figure 2 is a side elevation thereof; and

Figure 3 is a plan view thereof.

The dominant features of the design reside in the portions shown in full lines.

I claim:

The ornamental design for a machine for de-burring and polishing metal articles or the like, substantially as shown and described.
